UNITED STATES PATENT OFFICE.

ALBERT SCHLUMBERGER, OF PARIS, FRANCE.

SAFETY-PAPER.

SPECIFICATION forming part of Letters Patent No. 481,770, dated August 30, 1892.

Application filed January 4, 1892. Serial No. 417,035. (Specimens.) Patented in France May 22, 1891, No. 213,226.

To all whom it may concern:

Be it known that I, ALBERT SCHLUMBERGER, a resident of the city of Paris, France, have invented a new and useful Improvement in 5 Safety-Paper, (for which I have obtained a patent in France, No. 213,226, dated May 22, 1891,) of which the following is a specification.

The object of the present invention is to provide paper to be employed for bank-notes, 10 bonds, checks, and similar papers of value, or for documents and legal instruments in such a manner as to render forgery of such papers impossible.

This invention consists in paper for bank- 15 notes, bonds, checks, &c., printed exactly alike on both sides and in such a manner that both impressions coincide perfectly, so that upon holding the paper against the light only one single impression is apparent. Each of the 20 two impressions is, moreover, made in two or more colors, the colors on one side being arranged in the reverse order to those on the other, so that the impression appears in two or more colors by reflected light, while under 25 transmitted light only one color (the compound color resulting from the mixture of two of the colors employed) appears.

In the accompanying drawings I have represented a check-blank embodying my in- 30 vention.

In the drawings, Figure 1 represents the ob- 35 verse, and Fig. 2 the reverse, of such a check-blank as it will appear when the blank is turned over from right to left.

My invention is preferably carried out as follows: When it is desired to print in three colors on each side of the paper—*e. g.*, blue, 40 violet, and red—the ink-fountain is provided with three compartments containing the cor- responding blue, violet, and red pigments, and the said pigments are transferred in strips of the required width upon the fountain-roller. The pigments or inks are thence transferred to the doctor-roller in annular strips, thence upon 45 the distributing-rollers, and by these finally to the printing-form in straight strips. From the form the strips of color are transferred to the paper. This method of simultaneously imprinting one side of the paper with several 50 strips of color is well known and offers no difficulties. Nor is there any difficulty in imprinting the other (reverse) side with strips

of color coincident with those on the first (obverse) side. It is, however, new in my invention to select and employ such colors for each 55 pair of coincident or superincumbent strips that when the paper is held up to the light and therefore viewed by transmitted light all the coincident strips of color on both sides of the sheet will produce a single common com- 60 pound color only. It is, moreover, new to print designs upon these colored strips on both sides of the sheet which exactly coincide and cover each other and whereby the several colors are brought out in relief by reflected light. 65

Various suitable colors may be employed for printing. I find it advantageous to use cobalt-blue, madder-lake, a mixture of madder and cobalt or chrome-green.

In the drawings, A, B, and C represent sec- 70 tions or areas on the obverse, Fig. 1, of the check-blank, which are printed in blue, violet, and red, respectively, while A', B', and C' represent coincident areas and strips on the re- 75 verse, Fig. 2, of the check-blank printed in red, violet, and blue, respectively. By this arrangement the compound color on viewing the check-blank by transmitted light will be violet for all the sections, and the check-blank will appear of a uniform violet color on hold- 80 ing the same up to the light. Of course other colors may be employed without departing from the principle of the invention.

The insertion of the second printing form or stamp, as well as the imposition of the re- 85 versed sheet thereon, so that the color-strips as well as the designs on both sides of the sheet exactly coincide and cover each other, require a certain amount of skill and practice, it is true, and such work can be carried out 90 only in a printing establishment equipped with high-class printing-presses and employing skilled workmen. The preparation of the two engraved stamps, which must be ex- 95 actly symmetrical, especially requires extraor- dinarily exact workmanship, inasmuch as the minutest deviation in the designs on the sheet printed on both sides with the same de- sign but in different colors is discovered at once. The selection of the colors also is diffi- 100 cult and demands the knowledge of an expert. Precisely these difficulties afford great security against forgery by imitation, because this demands not only an exceedingly-high

order of engraving and expert knowledge of the pigment employed, but also an excellently equipped printing-office—*i. e.*, it requires advantages which are combined only in the best printing establishments.

What I claim, and desire to secure by Letters Patent, is—

1. A safety-paper for papers of value, documents, and the like, consisting in a sheet 10 printed on both sides with coincident designs in such a manner that on holding the paper against the light only one impression is apparent, substantially as shown and described.

2. A safety-paper consisting in a sheet 15 printed on both sides with coincident areas of various colors, the colors of the pairs of coincident areas all combining to produce the same compound color by transmitted light.

3. A safety-paper consisting in a sheet

printed on both sides with coincident designs, 20 the designs being arranged in coincident areas of various colors, the colors of the pairs of coincident areas combining to produce the same compound color.

4. A safety-paper consisting in a sheet 25 printed on both sides with coincident designs in various colors arranged in strips, the strips on both sides being coincident and the same colors being employed on both sides but arranged in reverse order.

In testimony whereof I have signed this specification in the presence of two subscribing witnesses.

ALBERT SCHLUMBERGER.
